SAW

Russell D. Knapp, Elko, Nev.

Application March 12, 1953, Serial No. 24,002

Term of patent 14 years

(Cl. D93—4)

To all whom it may concern:

Be it known that I, Russell D. Knapp, a citizen of the United States, residing at Elko, in the county of Elko and State of Nevada, have invented a new, original, and ornamental Design for a Saw, of which the following is a specification, reference being had to the accompanying drawing, forming part thereof.

Figure 1 is a plan view of a saw, showing my new design;

Figure 2 is an edge view thereof, and

Figure 3 is a plan view showing the reverse side of the saw shown in Figure 1.

I claim:

The ornamental design for a saw, as shown.
RUSSELL D. KNAPP.
